(57) CLAIM

The ornamental design for a side dish container comprising a lid and a base, as shown and described.

DESCRIPTION

FIG. 1 is a front perspective view of a side dish container comprising a lid and a base showing our new design;

FIG. 2 is a top plan view thereof;

FIG. 3 is a bottom plan view thereof;

FIG. 4 is a front elevation view thereof;

FIG. 5 is a rear elevation view thereof;

FIG. 6 is a left side elevation view thereof; and,

FIG. 7 is a right side elevation view thereof.

The broken line portion of the figure drawings is included to show unclaimed subject matter only and forms no part of the claimed design.
